ENVELOPE

Filed June 4, 1924

FIG. 2.

FIG. 1.

FIG. 3.

INVENTOR

BY *John C. Schilke*
W.H. Lieber
ATTORNEY.

UNITED STATES PATENT OFFICE.

JOHN C. SCHILKE, OF MILWAUKEE, WISCONSIN, ASSIGNOR OF ONE-HALF TO HERMAN FROEHLICH, JR., OF MILWAUKEE, WISCONSIN.

ENVELOPE.

Application filed June 4, 1924. Serial No. 717,707.

This invention relates in general to improvements in envelopes or similar wrappers for inclosing communications and other valuables preparatory to transmission thereof by mail.

An object of the invention is to provide an improved envelope structure which is simple in construction and efficient and practical in use.

10 It has heretofore been attempted to produce various envelope structures and attachments for the same, for the purpose of making the envelopes proof against being opened and the contents rifled, without detection. Some of the prior safety envelopes have failed to gain commercial consideration because they did not effectively accomplish the objects sought. Others have proven uncommercial because they were too 15 complicated and expensive.

The present invention contemplates the provision of a safety attachment for envelopes and the like, which is extremely simple, efficient, inexpensive and practical 20 in every way. The improved device besides being readily applicable at but slight additional cost, to envelopes or wrappers of ordinary standard construction, provides for compound sealing of the wrapper with substance which is not soluble in water thus 25 preventing opening of the seals by steaming. The improved safety appliance may be readily manufactured with the aid of dies, and when applied to an envelope, provides a durable wrapper which is capable of 30 withstanding considerable abuse without danger of destruction. The improvement besides insuring safe transmission of inclosures, affords excellent opportunities for advertising without necessity of printing the advertising matter upon the envelope 35 itself. These and other specific objects and advantages of the present improvement will be apparent in the course of the accompanying description.

A clear conception of several embodiments of the invention and of the commercial application thereof, may be had by referring to the drawing accompanying and forming part of this specification in which like reference characters designate the same or similar parts in the various views.

Fig. 1 is a rear view of an open standard

envelope having an improved safety appliance attached therein and showing a letter 55 partially inserted within the wrapper.

Fig. 2 is a rear view of one form of the improved safety appliance.

Fig. 3 is a rear view of a sealed standard envelope having an improved safety appliance associated therewith, a fragment of the envelope and safety appliance having been broken away.

Referring specifically to the embodiment of the invention disclosed in Figs. 1, 2 and 3, the standard envelope comprises a front portion which is not visible in the drawing; a back portion formed of three permanently connected triangular flaps 7, 8, 9; and a main triangular sealing flap 2 attached to the upper edge of the front portion and having a gummed strip 11 for attaching the main flap 2 to the rear flaps 7, 8, 9 in a well known manner. One form of safety appliance applicable to this type of envelope comprises a safety sheet 4 slightly smaller in size than the interior of the envelope and having an integral auxiliary safety flap 3 at the medial portion of its upper edge. As shown, the entire rear surface 6 of the safety sheet 4 and flap 3 is gummed, preferably with a mucilaginous substance which is relatively insoluble in water and hence capable of resisting destructive action of steam. The medial portion of the junction between the main sealing flap 2 and the front portion of the envelope is provided with a slit 10 which is slightly longer than the widest portion of the auxiliary safety flap 3.

When the form of safety appliance shown in Figs. 1, 2 and 3 is applied to an envelope such as shown, the gum on the lower portion of the rear surface 6 is softened and the safety sheet 4 is inserted within the envelope wrapper as illustrated in Fig. 1, whereupon the sheet 4 is permanently attached to the inner surfaces of the rear flaps 7, 8, 9. The letter 5 or other enclosure may then be inserted in the envelope between the front portion and the safety sheet 4. After the letter 5 has been completely inserted, the auxiliary safety flap 3 should be passed through the slot 10. The gummed strip 11 and the remaining exposed gummed surface 6 may then be pre-

pared for sealing whereupon the flaps 2, 3 may be folded and permanently sealed as shown in Fig. 3. With the envelope thus sealed, the main sealing flap 2 besides being attached to the flaps 7, 8, 9 by virtue of the gummed strip 11, is attached to the safety sheet 4 and to the auxiliary flap 3, thus providing a compound seal for the envelope.

From the foregoing description it will be obvious that with the present improvement an extremely simple, efficient, inexpensive and practical safety attachment is provided. The improved device may be applied either to standard or special envelopes at but slight additional cost and provides a double seal which cannot be opened and resealed without detection. The insert safety sheet of Fig. 2 may be manufactured with the aid of dies and serves to reinforce the envelopes to which it is applied. By permitting the safety flap to extend outside of the envelope, this flap may be provided with printed advertising matter and may also be additionally secured with sealing wax. The safety flap may moreover be sealed either to the front or the rear of the envelope and is subject to considerable modification in

form without departing from the present invention.

It should be understood that it is not desired to limit the invention to the exact details of construction herein shown and described, for various modifications within the scope of the claim may occur to persons skilled in the art.

It is claimed and desired to secure by Letters Patent:—

A safety envelope comprising an ordinary envelope wrapper having a main sealing flap and a slit directly at the junction between the main flap and the front of the wrapper, and an insert sheet secured to the inside surface of the rear of said wrapper and having an upper edge extending substantially across the wrapper closely adjacent to said junction, said sheet having an auxiliary flap formed for insertion through said slit and gummed for direct attachment to the exterior of said wrapper main flap only after being inserted through said slit.

In testimony whereof, the signature of the inventor is affixed hereto.

JOHN C. SCHILKE.
